ADVERTISING DEVICE

Application filed May 14, 1931. Serial No. 537,300.

This invention relates to advertising display devices and particularly to a magnetically operated device for use in connection with window displays and the like.

5 The principal object of this invention is a device of the character described which may be operated from the outside of the display window by any passerby for the purpose of selectively operating one or more devices 10 within the display window.

Another object of our invention is to provide an operating device of this character part of which may be placed on the inside of the show window and part on the outside, 15 these parts cooperating magnetically through the medium of the glass, and without any mechanical connection between the parts, as a result of which the necessity of drilling or otherwise cutting the glass or of making electrical or other connections from the outside 20 into the display window or show case is eliminated.

Another advantage of our invention resides in the fact that the operator is not endangered by handling any electric currents 25 which would be especially dangerous were the operator standing on the pavement or ground.

A similar advantage is that the operator 30 can operate the device and the machines on display only in a predetermined manner, and cannot in any way cause damage to the machine by improper operation of or by damaging the outside operating element.

35 A more specific object and advantage of our invention is an operating switch for this purpose which may be manufactured economically and in a large variety of forms, and which may be readily and easily placed in operating position, and does not require any change in the display window itself.

Another object of our invention is a device 40 arranged to intrigue the passerby by causing actuations of the machines inside of a display window through the medium of the glass front and with no visible connection between the part operated by the passerby and the machines within the display window and to direct his attention to each particular machine in turn, by permitting operation of each

machine selectively by the passerby himself.

Other objects and advantages will be 55 come apparent from the following specification in which reference is made to the drawings by reference numerals.

In the drawings:—

Fig. 1 is a somewhat diagrammatic illustration of a display window with the device 60 in position therein for operating the various machines being advertised.

Fig. 2 is a sectional view of the display window illustrated in Fig. 1 and is taken on a plane indicated by the line 2—2.

Fig. 3 is a front elevation of a form of 65 magnetic switch embodying the principles of our invention.

Fig. 4 is a cross sectional view of the switch 70 illustrated in Fig. 3 with the operating dial therefor in operating position.

Fig. 5 is an enlarged partial sectional view 75 taken on a plane indicated by the line 5—5 of Fig. 3.

Fig. 6 is a diagrammatic illustration of 80 one form of circuit used in combination with the switch for operating a large number of machines.

Referring particularly to Figs. 1 and 2 there is illustrated a display window in which 85 are a number of machines designated 2, 3, 4, 5 and 6, which it is desired to operate from the outside of the window. The display window is provided with the usual plate glass front 7 for protecting and guarding the machines. The switch element of our device 90 to which the machine to be operated may be magnetically or electrically connected is indicated at 10 and is arranged on the inside of the display window and preferably positioned against the inner face of the glass 7, 95 as better illustrated in Fig. 4.

A manually operated dial or other movable element 12 is positioned on the outside of the glass preferably in alignment with the switch 10 for operating the switch so that 95 the passerby may selectively operate any one of the devices in the window from the outside. In this manner his attention may be more effectively arrested and directed to each of the machines in turn. The elements 100

10 and 12 are associated magnetically through the medium of the glass 7 and are connected in no other manner. As a result of this arrangement the attention of the operator is retained, inasmuch as he can see no connection between the elements he operates and the machines operated thereby.

As mentioned it is often desirable to operate selectively one or more of the machines on display and we have shown a form of our invention by way of illustration which is arranged for this purpose. Furthermore, to more definitely focus the attention of the operator on the particular machine being operated, we have provided lights 13 connected one in parallel with each machine and positioned to illuminate the particular machine while it is being operated. By turning the dial 12 to predetermined positions each of the machines in turn may be rendered operative and at the same time illuminated, usually by closing electrical circuits connected with the respective machines. By turning the dial 12 to different positions relative to the switch 10 the circuits to each machine are in turn opened and closed. Since it is desirable that the dial 12 return to a normal position of rest and disconnect the machines when the passerby has released the dial, we may arrange the switch 10 so that when the dial returns to its normal position of rest the switch will connect the usual window flood lights with a source of power and accordingly will disconnect these lights when any particular machine is being operated.

The dial 12 may be mounted on any suitable pivot connection in a body 15 which is glued onto the glass of the window. The weight 9 is provided on the dial to overbalance the same and cause it to return to a predetermined normal position of rest when it is released by the operator. The particular number and arrangement of the machines, lights and circuits is largely optional, the above being given by way of illustration of an effective display and to better illustrate the features of our invention.

To accomplish these results we prefer to use a switch 10 such as illustrated in Figs. 3 and 4 and an electric hookup such as diagrammatically illustrated in Fig. 6. The switch 10 may be mounted on any suitable standard 14 through which the electric conductors may pass from the switch 10 to the respective circuits. In the form illustrated, the switch 10 comprises a circular body 16 on which are mounted a plurality of magnets, for example, three magnets 17, 18 and 19, may be used. These magnets are preferably positioned about 120° apart and equally spaced from the center of the circular body. All the magnets may be identical in form and similarly mounted so that the description of the magnet 19 only may be given.

Referring to Fig. 5, the magnet 19 may be

a bar magnet pivotally mounted in a yoke 20 which is secured to the circular body 16, the magnet being held between the yoke arms by a pivot 21 so as to swing freely about its pivot. A spring 22 which is shown as a leaf spring is secured intermediate its ends to the magnet 19 or the yoke 20, the free ends of the spring engaging the other of the two members so as to yieldably hold the magnet in a predetermined neutral position. Carried by or operably connected to the magnet 10 is a contactor 23. Arranged at each side of this contactor in the path of movement described thereby as the magnet swings about its pivot are complementary contactors 24 and 25, each of which is connected in a circuit later to be described. These contactors are preferably disposed one at each side of the contactor 23. In this illustrative form of our invention the magnets 17, 18 and 19 are positioned with the south poles pointing inwardly toward the center of the body 16 and extend radially with the north poles pointing outwardly from the center. The dial 12 carries a magnet 26 which may be a bar or horseshoe magnet. This magnet is secured to the dial so as to turn therewith. If a single magnet is used it should extend diametrically through the center of the dial with the magnet ends positioned so as to describe circles through the south pole, for example, of the magnets 17, 18 and 19 as the dial 12 is rotated. As the north pole of the magnet 26 passes the south poles of each of the magnets 17, 18 and 19, the poles of these latter magnets are attracted to the north pole 26, thus causing the magnets 17, 18 and 19 to turn about their respective pivots. For example, when the magnet 19 is thus attracted toward the north pole, the contactor 23 carried on the magnet 19 is brought into contact with the contactor 25. Similarly as the south pole of the magnet 26 is disposed in front of the south pole of the magnet 19, it repels this pole of the magnet 19, causing the magnet to swing in the opposite direction about its pivot, thus bringing the contactor 23 into contact with the contactor 24, for purposes later to be described.

We prefer that the elements 17, 18 and 19 be permanent magnets instead of ordinary iron bars, so that two simple contacts may be obtained for each element. However, instead of magnetizing the members 17, 18 and 19, these may be of ordinary iron and have only single contact each, and thus be attracted by the magnet to effect this contact. A double contact is also possible when these elements are of iron and may be obtained by arranging the magnetic means 26 so that the elements 17, 18 and 19 are each attracted on one side of the pivot point to the magnet 26 to effect one contact and are attracted on the opposite sides of the pivot points to swing the elements in the opposite direction for effecting another contact. Again, if the elements 17, 18 and 19

are permanent magnets, iron elements instead of a magnet 26 may be provided in the dial 12 so that when brought opposite to these elements it will effect movement thereof. As stated however, we prefer that both the element 26 and the elements 17, 18 and 19 be permanent magnets so that a heavier flux is obtainable and operation better insured.

Referring again to the preferred form of our invention, when the dial 12 is rotated each of the magnets 17, 18 and 19 will be moved to one or the other of its contact positions, thus closing the circuits and operating a device in the window. In the case of the heavier machines, for instance, washing machines, electric fans and the like, a power circuit of 110 volts is usually required. In machines operating on such a circuit it is usually damaging to the machines to start and stop them too quickly, and furthermore causes a considerable arc on the contactors which tends to burn or otherwise deleteriously affect the contacts and adjacent working parts of the switch. To eliminate these disadvantages and to prevent starting and stopping the machines as the dial is being moved from one position to another, we find it expedient to use a circuit such as will now be described, and to provide in the circuit a retarded relay 30 so that not only must each of the magnets 17, 18 and 19 be operated to cause a contact but also retained in such position for a short interval before the power circuit will become operative and start the machine. Since the circuits for each of the magnets may be the same, we shall describe the circuit associated with the magnet 19 only.

Assuming a passerby has revolved the dial 12 so as to position the south pole of the magnet 26 in front of the south pole of the magnet 19, the like poles will repel each other and consequently the magnet will be swung about its pivot point to the position shown in Fig. 6, bringing the contactor 23 carried by the magnet into contact with the contactor 24. The magnet 19 may be connected to one side of a low voltage source of electric current and the contactor 24 connected to the other side, so that upon contact of these elements the circuit is completed. Such a circuit could directly operate a device utilizing low voltage power supply, but inasmuch as a heavy current would be detrimental to the parts as described, we prefer to use a higher voltage power circuit and to operate it from the low voltage circuit. The circuit associated with the magnet 19 may comprise a battery in which the positive line 33, for example, passes through the magnets 17, 18 and 19. Connected in this line is the coil of a retarded relay 30. The negative line 35 of this circuit may pass to the coil of the operating relay 36 and thence to the contactor 24. A lead 38 is connected to the line 35 between the battery and relay 36 and passes

to the coil of the operating relay 37 and then to the contactor 25. When the magnet 19 is actuated as described, to cause contact between the contactor 23 and the contactor 24, a closed circuit is formed from the battery 70 through the retarded relay 30 and the operating relay 36. The movable contactor 40 of the operating relay 36 immediately closes the power line 41 connecting the machine to be operated with one side of the retarded relay 75 30, for example, with the movable contact 43. Slightly later the contact 43 moves to connect the line 41 to one side of a source of power, through the stationary contactor 42. The other power line 44 from this source 80 of power may serve as a common line to each machine to be operated. Due to the delayed operation of the retarded relay, the magnet 19 must be retained in position to retain the contactors 23 and 24 in contacting relation 85 for a short interval before closing of the power circuit results.

Thus, as described, the passerby must retain the dial 12 for a short interval at one of the operating positions before operation is 90 obtained, and revolving of the dial 12 will not rapidly start and stop each machine in turn.

A similar hookup may be used for the relay 37 so that upon contact of the contactor 95 23 with the contactor 25 another machine may be operated. A separate operating relay is provided for each contact, the retarded relay being common to all.

The circuits we have shown are illustrative of a number of possible circuits which may be used, depending upon the particular device to be operated, voltage required, etc.

From the foregoing description it is apparent that not only is the passerby protected from electric currents, but likewise it would be impossible for him to improperly operate the machine on display. Furthermore, since there is no visible connection between the dial and the switch and since each 105 of the machines may be operated selectively by him, consequent upon his operating the dial, his attention will be retained and focused directly on each machine in turn.

While we have described our invention 115 particularly adapted to use in connection with a display window or show case having a glass or transparent front, obviously it is not necessary that it be limited to this use, as quite a desirable advertising attraction is 120 afforded by placing the operating elements in spaced relation with no visible connection therebetween. It is pointed out, however, that if a solid and imperforate wall such as the glass 7 used between the switch and the 125 dial, that no ferrous substance should be included in the imperforate wall in a position such as to affect the magnets. Again it may be pointed out that while we prefer to use such a switch to form various electric con- 130

nections for operating the machines, it may be in some cases that the inside element may directly operate some device, the power being obtained by the manual operation of the dial. In any case, however, the operation is effected by the passerby from the outside of the window, the outside and inside elements operating by magnetic attraction and repulsion only.

10 Having thus described our invention, we claim:

1. In an advertising device, the combination with an apparatus to be actuated for advertising the same and a display case window including an imperforate glass wall in substantially upright position for guarding said apparatus while displaying the same, of a movable element to effect actuations of said apparatus consequent upon movement of said element, said element being guarded by said glass wall, a manually movable element disposed on the opposite face of said glass wall and accessible to the public, said manually movable element and the first mentioned movable element being adapted to be associated magnetically through the medium of the glass wall for moving the first mentioned element consequent upon a predetermined movement of the manually movable element.

15 2. The combination with a display case having an imperforate glass wall and a product to be advertised on display in the case and guarded from the public thereby and by said glass wall, and visible to the public through said glass wall, of a manually movable element mounted on the outside of said glass wall and operable from the outside of the case by a member of the public, a movable element within the case, said element being associated with the manually movable element magnetically only and through the medium of said glass wall for moving the element inside of the case consequent upon movement of the manually movable element and means operable by the said element which is inside of the case for directing attention of such member of the public to the said product to be advertised.

3. The combination with a display window having an imperforate glass wall and a set of actuatable devices on display in said window, of means operable from the outside of the window for selectively effecting actuations of said devices, said means including a manually movable element mounted on the outside of the glass wall and accessible to the public, and a movable element inside of the wall and guarded thereby and associable selectively with the devices on display, said elements being associated through the medium of the glass wall magnetically only for moving the last mentioned element consequent upon a predetermined movement of the manually movable element.

4. The combination with a display window

including an imperforate glass wall and plurality of visibly actuatable devices on display in said window and guarded from the public by said glass wall, of means operable from the outside of the window by a member of the public through the medium of the glass wall for offsetting actuations of said devices, said means including a manually movable element carried on the outside of the glass wall, and a movable element inside of the wall and guarded thereby and associable with one of said devices on display when moved to one position and associable with another of said devices when moved to another position, said elements being associated magnetically only through the medium of said wall for movement of the last mentioned element consequent upon movement of the manually movable element in a predetermined manner.

5. The combination with a display window having an imperforate glass wall and an electrically operable apparatus within said window to be visibly displayed to the public therethrough when operated and a switch for initiating and arresting actuations of said apparatus, of means for actuating said switch from the outside of said window, said means including a movable element arranged in the window behind the glass wall, and a manually rotatable element supported by the glass wall on the outside thereof and accessible to the public, said elements being associated with each other magnetically only through the medium of the glass wall for movement of the first mentioned element consequent upon movement of the manually movable element in a predetermined manner.

6. The combination with a display window having an imperforate glass wall and a plurality of electrically operable devices with visibly movable elements, said devices being arranged to be advertised in said window and guarded thereby and connected in circuits with a source of electrical energy, and switches for opening and closing said circuits for operating the devices, of means for operating said switches selectively from the outside of the window, said means including settable means arranged inside of the window and guarded thereby, a manually settable element arranged on the outside of the glass wall, said element and means being magnetically associated with each other through the medium of said wall.

7. The combination with a display window having a glass wall and a plurality of electrically operable devices with visibly movable elements within said window and guarded by said wall against direct access of the public to said devices, and circuits connecting each of the devices with a source of electrical energy, and switch means for opening and closing said circuits, of movable elements associated one with each of said switches for operating the same consequent upon move-
